UNITED STATES PATENT OFFICE.

JAMES R. MOFFATT, OF CHICAGO, ILLINOIS, ASSIGNOR TO UNION SPECIAL MACHINE COMPANY, OF CHICAGO, ILLINOIS, A CORPORATION OF ILLINOIS.

FEEDING MECHANISM FOR SEWING MACHINES.

Application filed April 19, 1921. Serial No. 462,571.

To all whom it may concern:

Be it known that I, JAMES R. MOFFATT, a citizen of the United States, residing at Chicago, in the county of Cook, State of Illinois, have invented certain new and useful Improvements in Feeding Mechanisms for Sewing Machines, of which the following is a description, reference being had to the accompanying drawing and to the figures of reference marked thereon.

The invention relates to new and useful improvements in feeding mechanisms for sewing machines, and more particularly to a feeding mechanism which includes a feed dog mounted beneath the work support and operating through slots in the work support for engaging and feeding the material.

An object of the invention is to provide a feed dog supporting and operating means which permits the feed dog to be shifted laterally, or in a direction at right angles to the line of feed, to center the fabric engaging portions thereof in the slots through which they operate.

A further object of the invention is to provide a feeding mechanism wherein the means for supporting and operating the feed dog is so constructed as to permit the working position of the fabric engaging portions of the feed dog to be centered in the feed slots through which they operate; or, in other words, to be shifted in the line of feed.

These and other objects will in part be obvious and will in part be hereinafter more fully disclosed.

In the drawings which show by way of illustration one embodiment of the invention—

Figure 1 is a view in top plan of a portion of a sewing machine having my improvement embodied therein, and with a part of the work support broken away to show the feed dog supporting means beneath the work support;

Figure 2 is a view partly in vertical section and partly in elevation from the left hand end of the machine;

Figure 3 is a view partly in section and partly in rear elevation of the same;

Figure 4 is a longitudinal sectional view on the line 4—4 of Fig. 1;

Figure 5 is an enlarged view, partly in section, of the crank pin disc on the main shaft;

Figure 6 is a perspective view, with parts separated, showing feed rocker, feed bar and feed dog; and

Figure 7 is a section on line 7—7 of Figure 6.

The invention is directed broadly to a feeding mechanism of the type wherein a feed dog is mounted beneath the work support and is provided with fabric engaging sections operating through slots in the work support or throat plate forming a part of the work support. This feed dog is carried by a feed bar which is pivotally connected to a feed rocker. The feed rocker is provided with spaced supporting lugs in which is mounted a bar or shaft to which the feed bar is fixedly connected. This bar or shaft is secured from endwise movements in the lugs by adjustable collars. By loosening the collars or loosening the connection between the feed bar and the bar or shaft mounted in the lugs, the entire feed bar may be moved laterally, or in a direction at right angles to the line of feed, for positioning the fabric engaging sections of the feed dog centrally of the slots in the throat plate.

The feed rocker is operated by an arm connected to a crank on the main shaft. On said crank is an eccentric sleeve which is clamped in the end of the arm and by adjusting this sleeve the working position of the fabric engaging sections of the feed dog may be shifted back and forth and thus centered relative to the longitudinal length of the slots in the throat plate.

Referring more in detail to the drawings, my improved feeding mechanism is shown as applied to a sewing machine having a bed plate 1, on which is mounted a work support 2. The work support 2 is provided with a throat plate 3 which is secured to the work support by suitable screws 4—4, and, in fact, becomes a part of the work support. This throat plate is provided with needle holes 5—5 and with feed slots 6, 7 and 8. Mounted beneath the work support is a feed dog 9, which in turn is provided with fabric engaging sections 10, 11 and 12. These fabric engaging sections respectively extend through the slots 6, 7 and 8, and engage the fabric resting on the work support and throat plate to feed it a stitch length.

This feed dog 9 is provided with a shank 13, which is slotted at 14. The shank 13 fits

in a recess in a feed bar 15, and a screw 16 passing through the slot 14 rigidly clamps the shank of the feed dog in the recess in the feed bar. Attached to the feed bar 15 is a plate 17. The feed bar carries a hardened plate 18, which rests on an eccentric 19, carried by the main shaft 20. The plate 17 engages the underface of this eccentric and the eccentric operates to raise and lower the feed bar 15.

At the rear of the machine there is a feed rocker 21 which is provided with downwardly extending lugs 22—22, which are secured to a shaft 23 by means of set screws 24. The shaft 23 is mounted in lugs 25—25 carried by the bed plate 1, so that said shaft may freely rock in said lugs. At one end of the shaft 23 there is a collar 26, which is secured to the shaft 23 by a set screw 27, which is not spotted, so that said collar 26 may be shifted endwise of the shaft 23. At the opposite end of the shaft 23 there is a similar collar 28, which is secured to the shaft by a set screw 29. These collars bear against the outer faces respectively of the lugs 25—25.

Said feed rocker 21 is also provided with upwardly extending lugs 30—30, in which is mounted a shaft 31, so that said shaft may freely turn in said lugs 30. The feed bar 15 is provided with integral sleeves 32—32, which are mounted on this shaft 31 and these sleeves are secured to the shaft by means of set screws 33, so that the feed bar is fixed to the shaft 31. On the right hand end of the shaft 31 there is a collar 34 which is secured to the shaft by a set screw 35 which is not spotted, so that said collar may be shifted endwise of the shaft 31. At the opposite end of the shaft 31 there is a similar collar 36, secured thereto by a set screw 37. These collars bear against the outer faces respectively of the lugs 30—30.

Attention is particularly called to the fact that the distance between the outer faces of the lugs 22—22 is considerably less than the distance between the inner faces of the bearing lugs 25—25, so that by loosening the collars 26 and 28, the shaft 23 may be shifted endwise in the lugs 25—25 and thus the whole feed rocker shifted endwise or transversely of the direction of its rocking movement and the direction of movement of the feed dog by the sewing machine. It will be readily seen that this endwise shifting of the feed rocker results in a lateral shifting of the feed bar and through this lateral shifting of the feed bar the fabric engaging sections 10, 11 and 12 of the feed dog may be centered in the slots 6, 7 and 8, in which they work. This is a great advantage as it eliminates a "close" milling operation between the lugs 22—22 and 25—25, or the bending of the feed bar or the filing away of the shank of the feed dog, or in some other way the reshaping or reforming of the metal to center

the fabric engaging sections in the throat plate.

Instead of shifting the entire feed rocker, the feed bar alone may be shifted. The distance between the outer faces of the sleeves 32—32 is less than the distance between the inner faces of the lugs 30—30, and, therefore, by either loosening the set screw 33 and shifting the feed bar on the shaft 31, or loosening the collars 34 and 36 and shifting the shaft 31 endwise, the feed bar may be shifted laterally and thus the fabric engaging sections of the feed dog properly centered in the slots in the work support.

The feed rocker is oscillated to impart back and forth movements to the feed dog by means of an integral arm 38. This arm 38 is split at 39, as is clearly shown in Figure 6, and is provided with a cylindrical recess 40, into which the split end leads. Located in this cylindrical recess 40 is a split sleeve 41, which has a flanged head 42 notched, as indicated at 43. Said sleeve is split, as indicated at 44, and has a cylindrical opening 45 which is eccentrically disposed relative to the center of the sleeve and the center of the recess 40. The split end of the arm 38 carries a set screw 46 by means of which the sleeve 41 may be fixedly clamped in the outer end of the arm 38. By loosening the screw, it will be apparent that the sleeve may be readily adjusted through the aid of the notches in the flange carried thereby. Clamped in said cylindrical opening 45 by the screw 46 is a pivot pin 47, the center of which is, of course, eccentric to the center of the sleeve 41. Loosely engaging the pivot pin 47 is one end of a link 48 and said link at its other end engages a crank pin 49, carried by a plate 50, which is mounted to slide back and forth in a slot 51 in a disc 52 secured to the end of the main shaft 20. A screw 53 is threaded through said plate 50 and is held from endwise movement by a bracket piece 54, lying between collars carried by the screw, and said bracket piece is secured to the disc 52 by means of screws 55. By turning the screw 53 the crank pin 49 is shifted toward and from the center of the shaft for varying the stroke of the feed dog. When the pivot pin 47 is shifted through the adjusting of the sleeve 41, the arm 38 will be swung toward or from the crank pin 49, and the swinging of the arm 38 will change slightly the working position of the fabric engaging sections of the feed dog. If, therefore, when the parts are assembled, it is found that the feed dog is working too close to the front end of the slots 6, 7 and 8, then this pin 47 is shifted so as to move the working position rearwardly slightly and thus center it in the longitudinal length of the feed slots.

From the above, it will be apparent that I have provided means whereby, after the ma-

chine is set up, the fabric engaging sections of the feed dog may be centered in the feed slots in the work support, so that they will move back and forth without binding 5 against the side walls of the slot; and, on the other hand, the stroke of the feed dog may be shifted so that the center of the longitudinal stroke of the feed dog will be centered with the longitudinal length of the 10 slots.

It is obvious that minor changes in the details of construction and the arrangement of parts may be made without departing from the spirit of the invention, as set 15 forth in the appended claims.

Having thus described my invention, what I claim as new and desire to secure by Letters Patent, is:

1. A feeding mechanism for sewing machines including in combination a work support having feed slots therein, a feed dog mounted beneath the work support and having fabric engaging sections extending through said slots, means for raising and 20 lowering the feed dog, means for moving the feed dog back and forth, said last named means including adjustable devices for varying the working position of the fabric engaging sections of the feed dog without 25 changing the length of the feed stroke, whereby the same may be centered longitudinally of the respective slots in which 30 said sections operate.

2. A feeding mechanism for sewing machines including in combination a work support having feed slots therein, a feed dog having fabric engaging sections working in 35 said slots, a feed bar supporting said feed dog, means for raising and lowering the feed 40 bar, a feed rocker for moving the feed bar back and forth, means for oscillating said 45 rocker, devices connecting the feed bar to the feed rocker, and devices for supporting said feed rocker, one of said devices being manually adjustable, whereby the feed bar 50 may be shifted laterally for centering the fabric engaging sections thereof in their respective slots, and means whereby the working 55 position of the fabric engaging sections 50 of the feed dog may be shifted longitudinally of the feed slots for centering said sections longitudinally of the respective slots in which they operate and without varying the length of the feed stroke.

3. A feeding mechanism for sewing machines including in combination, a work support having feed slots therein, a feed dog having fabric engaging sections working in 60 said slots, a feed bar carrying said feed dog, means for raising and lowering the feed bar, a feed rocker, an arm integral with said feed rocker, a pin carried by the outer end of said arm, a link connected to said pin for oscillating the arm for moving the feed 65 dog back and forth, and means whereby said

pin may be shifted in said arm for varying the working position of the fabric engaging sections of the feed dog in their respective slots.

4. A feeding mechanism for sewing machines including in combination, a work support having feed slots therein, a feed dog having fabric engaging sections working in 70 said slots, a feed bar carrying said feed dog, means for raising and lowering the feed bar, a feed rocker, an arm integral with said feed rocker, a sleeve adjustably mounted in the outer end of said arm, a pin eccentrically carried thereby, means for engaging 75 said pin for oscillating the arm, and means for clamping said sleeve in an adjusted position.

5. A feeding mechanism for sewing machines including in combination, a work support having feed slots therein, a feed dog having fabric engaging sections working in 80 said slots, a feed bar carrying said feed dog, means for raising and lowering the feed bar, a feed rocker, an arm integral with said feed rocker, a split sleeve mounted in the 85 outer end of said arm, the outer end of said arm being split and having a clamping screw for clamping said sleeve, said sleeve having an opening eccentrically located therein, a pin mounted in said opening, and a link connected to said pin for oscillating said arm.

6. A feeding mechanism for sewing machines including in combination, a work support having feed slots formed therein, a feed dog having fabric engaging sections working in 90 said slots, and means for supporting and actuating said feed dog including devices whereby the fabric engaging sections may be shifted laterally in their respective slots for centering the same relative to the slots and whereby the working 95 position of said fabric engaging sections may be shifted longitudinally of their respective slots for centering the same longitudinally 100 of the slots.

7. A feeding mechanism for sewing machines including in combination, a work support having feed slots therein, a feed dog having fabric engaging sections working in 105 said slots, a feed bar carrying said feed dog, means for raising and lowering the feed bar, a feed rocker, an arm integral with said feed rocker, a split sleeve mounted 110 in the outer end of said arm, a pin in said sleeve, a link connected to said pin for oscillating said arm on the feed rocker, and a clamping screw for the outer end of said arm for clamping the pin in the split sleeve 115 and clamping the sleeve in said split arm.

8. A feeding mechanism for sewing machines including in combination, a feed dog, a feed bar, a feed rocker to which said bar is connected, a bed plate having spaced lugs, a shaft mounted in said lugs, collars on the 120 125 130

- 4
- outer ends of said shaft and engaging respectively the outer faces of said lugs to prevent endwise movement of said shaft and permitting said shaft to be adjusted endwise and held in adjusted positions, said feed rocker having sleeves through which said shaft extends, said sleeves being fixed to the shaft and having their outer faces a less distance apart than the distance between the inner faces of the lugs carrying said shaft.
9. In a sewing machine, the combination of a bed plate, a feed rocker mounted thereon, means for oscillating said feed rocker, a feed dog, a feed bar carrying said dog, said feed bar having spaced sleeves, said feed

rocker having spaced sleeves, a shaft passing through said sleeves for connecting the feed bar to the feed rocker, said sleeves on the feed bar being fixed to the shaft, and collars 20 adjustably mounted on the outer ends of said shaft and bearing against the outer faces of the sleeves on the feed rocker, the distance between the outer faces of the sleeves on the feed bar being less than the 25 distance between the inner faces of the sleeves on the feed rocker, whereby the shaft may be adjusted endwise.

In testimony whereof, I affix my signature.

JAMES R. MOFFATT.
